UNITED STATES PATENT OFFICE.

EPHRAIM U. THOMPSON, OF BRISTOL, MAINE.

IMPROVEMENT IN SETTING UP SHIPS' RIGGING.

Specification forming part of Letters Patent No. 29,204, dated July 17, 1860.

To all whom it may concern:

Be it known that I, EPHRAIM U. THOMPSON, of Bristol, in the county of Lincoln and State of Maine, have invented a certain new and useful Apparatus for Setting Up Ships' Rigging; and I do hereby declare the following to be a full, clear, and exact description thereof, reference being had to the accompanying drawings, making part of this specification.

My invention consists, first, in a device for grasping the ends of the shrouds, so that when the shrouds are set up every fiber bears its proportionate share of the strain. At the same time the ends of the shrouds are sheathed and protected from the weather, thus preventing their decay.

Second, in a peculiar construction and combination of lanyard and jack, for the purposes hereinafter explained.

In the accompanying drawings, Figure 1 represents a front elevation of the lanyard and jack, or setting-up device. Fig. 2 is a side elevation of the same. Fig. 3 is a longitudinal section of the thimble, showing the end of the shroud and fid partly in section.

A represents the shroud.

B is a thimble attached to the end of the shroud.

a is a ferrule fitting the end of the thimble.

C is a fid formed of hard wood.

D is a cap fitting the end of the thimble.

F is a screw-bolt passing through the cap D into the end of the fid C.

b represents ears or lugs cast upon the periphery of the thimble B.

e are metal straps fitting over the ears b, and attached to the upper end of the lanyard E by an eyebolt, e. The straps are prevented from spreading, and thereby slipping off the ears, by a ring, d, fitting over their ends. The lanyard is formed of two pieces of metal, E E', fitting one within the other, of which the upper portion, E, is attached to the shroud and the lower portion, E', to the ship. The portion E is a solid bar of iron flaring downward on two sides. The portion E' is formed of two elastic bars fitting over the portion E, as represented, and united below it in a solid bar, f, adapted to be fastened either to the chain or to replace the chain and be attached directly to the ship's side.

g are loose collars which fit over the two parts of the lanyard, and serve the purpose of locking them together in any position in which they may be set.

H is an iron bar constructed with a yoke, h, forming at its lower end a nut with a left-hand thread.

I is a yoke attached at its lower end to the part f' of the lanyard by means of a bolt, i, and forming at its upper end a nut with a right-hand thread.

J is a right and left hand screw fitting the nuts in the yokes H and I, and rotated by a lever, L, so as to cause the said yokes to approach or recede from each other, as desired.

K is a dog hooking over the top of the upper portion, E, of the lanyard, and attached to the bar H by any one of the holes h'.

The operation is as follows: The thimble is first passed over the end of the rope. The latter is then opened and the fid inserted and the rope end hawsed down onto it, being careful to keep the strands in proper relative position. When fitted snug onto the fid, worm and parcel and serve as in case of other fitting. A compress, M, of thin sheet metal is then passed around, as seen in Fig. 3, its ends overlapping to permit its contraction upon the rope. Heave such turns as are needful in the rigging by means of the projecting end of the fid, and haul down the thimble to the position shown in the drawings, drive the fid home, and saw off the projecting end flush with the lower edge of the thimble. Next bore into the end of the fid and apply the cap D and screw F. Then fix the straps e to the thimble, as previously explained, attach the dog K and yoke I to the respective ends of the lanyard, rotate the screw J until the shroud is drawn thoroughly taut, and then drive down to collars g, so as to hold the two portions of the lanyard firmly in position. The jack H I J K may then be removed and the shroud will remain securely fixed.

I claim as new and of my invention herein—

1. The combination of the fid C and thimble B, constructed, applied, and operating substantially as and for the purposes set forth.

2. The lanyard E E', constructed and operating substantially as described.

3. The described combination of the jack H I J K and lanyard E E', operating as set forth.

In testimony of which invention I hereunto set my hand.

E. U. THOMPSON.
